UNITED STATES PATENT OFFICE.

COLLIER MONROE, OF WACO, TEXAS.

HAIR CLIPPER.

1,417,094.

Specification of Letters Patent. Patented May 23, 1922.

Application filed March 25, 1922. Serial No. 546,553.

To all whom it may concern:

Be it known that I, COLLIER MONROE, a citizen of the United States, residing at Waco, in the county of McLennan and State of Texas, have invented certain new and useful Improvements in Hair Clippers, of which the following is a specification.

The object of the invention is to improve the structure of the clipper forming the subject matter of my co-pending application, Serial No. 469,842; and particularly to simplify the manufacture as well as to provide several advantageous features.

One of the aims of the invention is to obviate the post employed in my former invention and to provide a more lasting and efficient pivotal bearing for the lever. Another result sought to produce is a more readily and more easily assembled device.

In carrying out the invention I provide the actuating lever with an integral depending stud which engages in a socket in the bridge, thus giving the lever a more ample pivotal bearing and reducing the wear which would result from the hole in the lever receiving a fixed post. The cover plate is fastened in position so that the tension plate and compression screw may be removed without exposing the driving posts or soiling the fingers with grease; also the upper cutter blade may be removed at the same time.

A further improvement is had by conforming the driving surfaces of the teeth of the gear to the contour of the spiral driving member, whereby a more positive drive is produced, than where the spiral member merely contacts with the upper or lower edges of the teeth.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a plan view of a device constructed in accordance with my invention,

Fig. 2 is a side elevation of the same,

Fig. 3 is a plan view of the tension plate removed and a portion of the cover plate broken away, another portion being in section.

Fig. 4 is a longitudinal vertical sectional view.

Fig. 5 is a face view of the volute gear disk,

Fig. 6 is a detail showing the engagement between the gear disk and the gear, and

60

Fig. 7 is a detail of the gear teeth.

In the drawings the numeral 10 designates a casing having a reduced shank 11, at its rear end. The forward end of the casing is inclined and a cutter blade 12 is suitably fastened thereto. At the forward end of the casing a transverse bridge 13 is provided which has a socket 14 intermediate its ends for receiving a depending pivotal stud 15 of an operating lever 16. The 65 stud 15, is integral with the lever and the latter is supported on the bridge 13, thus an ample bearing surface is provided and wear at the pivotal point is reduced to a minimum. This arrangement has been found a 70 decided improvement over an operating lever pivoted on a fixed post, besides simplifying the manufacture of the device.

The fixed cutter blade 12 is provided with the usual upstanding rectangular lugs 17 80 which are received in rectangular slots 18, in the usual reciprocating blade 19. The blade 18 has a central notch 20 in its rear edge which is adapted to receive the arm 21 on the forward end of the operating lever 16. The 85 blade 19 is mounted on the blade 12 in the usual manner and is adapted to be reciprocated when the said lever is swung.

The lever 16 has a central longitudinal slot 23, in its rear end receiving a slide block 90 24 which is confined on an eccentric pin 25 carried on the upper side of a gear wheel 26. The gear wheel is supported on a stud 27 mounted in the bottom of the casing 10. In the shank 11, I dispose longitudinally of 95 the device a shaft 28, which is provided with a circumferential groove 29, receiving the end of a set screw 30 whereby said shaft is held against longitudinal displacement. The rear end of the shaft projects into a 100 counter bore 31 and is adapted to be connected with a flexible shaft (not shown), which is driven by an electric motor or any other means. The screw 30 also fastens a spring latch 32, which overhangs the counter 105 bore 31 for holding the flexible shaft therein.

On the inner or forward end of the shaft, I mount a volute gear disk 33 which has on its face a spiral or volute driving member 34. The disk is placed substantially tangentially 110 to the gear 26 and the outer end of the spiral member 34 is reduced so as to more

readily enter between the teeth of the gear wheel. It will be seen that the outer end of the spiral member engages with the teeth on a line which substantially registers with the 5 central position of the lever 21. This point of engagement is substantially in alinement with the pivot points of the lever and the gear 26 and it will be seen that when the block 24 reaches either end of the stroke it 10 will also be alined with said pivot points and the volute gear will be exerting its force on the gear 26 at right angles to this alinement, consequently there will be no tendency on the part of the block and lever to bind 15 and a much smoother operating device will be had. It is pointed out that wear will have little or no effect upon the transmission of motion to the gear wheel 26.

As is best shown in Fig. 6, the teeth of 20 the gear 26 are conformed to the contour of the spiral member 34, whereby the driving surface is amplified and a more positive drive is had than where the said member merely engages the upper or lower edges of 25 the teeth.

The upper side of the casing is reduced to receive a flat cover plate 35 conforming to the contour thereof, said plate having an upset portion 36 over the gear disk 33. The 30 plate is secured in position by screws 50 which are passed through apertures in the forward end thereof and engaged in the bridge 13. Integral with the top side of the plate 35 is an upright socket 51 which is 35 preferably in alinement with the pivotal stud 15 of the lever 16, the said socket being internally screw threaded.

I also provide a tension plate 37 which 40 overhangs the sides of the casing at the forward end thereof and has its rear end resting on the cover plate. The tension plate has its front edge 38 contacting with the blade 19 throughout its length whereby it exerts an even pressure on said blade and 45 holds it in the desired relation with the blade 12. A suitable aperture or opening is provided in the said tension plate in alinement with the socket 51, whereby a thumb screw 52 may be passed therethrough and engaged in said socket, as will be best seen in 50 Fig. 4. Surrounding the upper portion of the said screw and fixed to the underside of the head 53 thereof is a coiled tension spring 54, adapted to engage the top of the tension plate 37. It will be readily seen that 55 by adjusting the said screw 52, the pressure of the tension plate on the blade 9 may be regulated.

In obviating the pivot post shown in my 60 copending application, it is pointed out that a more lasting bearing is had for the operating lever 16. Among other advantages the improvements set forth herein permit of the removing of the tension plate 37 without disturbing the cover plate 36 or expos-

ing any of the driving mechanism. At the same time the reciprocating blade 19 may be removed, as is obvious. These features make for convenience in handling the device, and by virtue thereof such adjustments may be 70 made without soiling the hands with grease from the internal parts.

As a matter of convenience the casing 10 is indented on each side at 42 and the rear of the plate 37, is contracted as well as 75 curved, whereby the device is more easily held in the hand of the operator. The shank is provided with a slot 43, so that the clipper may be supported when not in use by hanging it on a suitable projection. 80

What I claim is:

1. In a hair clipping device, a casing, a cutter blade carried at the front end of the casing, a reciprocating cutter blade operating on the first named cutter blade, an operating lever having a depending pivot element mounted in the casing and engaged with the reciprocating blade, means for swinging the lever to reciprocate said blade, a cover plate mounted on the casing and combining the lever in position, a tension plate having one end resting on the cover plate and the other end engaging the reciprocating blade, a thumb screw passing through the tension plate and engaging the 95 cover plate, and a spring means between the screw and the plate for placing the latter under tension.

2. In a hair clipping device, a casing, a cutter blade carried at the front of the 100 casing, a reciprocating cutter blade operating on the first named cutter blade, an operating lever having a projecting pivot element carried thereby, said lever engaging at its forward end the reciprocating 105 cutter blade, means for swinging the rear end of the lever for reciprocating said blade, a cover plate mounted on the casing over the lever, means for fastening the cover plate in position, a tension plate mounted over the 110 cover plate and having one end bearing thereon, the other end of the tension plate bearing on the reciprocating blade, a thumb screw passing through the tension plate and having screw threading engagement with 115 the cover plate, and a spring tension confined between the head of the thumb screw and the tension plate for placing the latter under tension.

3. In a hair clipping device, a casing, a 120 bridge extending transversely at the forward end of the casing and having a bearing socket, an inclined blade secured to the casing, a reciprocating blade mounted on the first named blade, an operating lever having a depending stud engaging in the socket of the bridge and mounted to swing on said bridge, the forward end of the lever engaging the reciprocating blade, rotating means for imparting a swinging movement to the 130

5 rear end of the lever, a cover plate fastened on the casing and confining the lever on the bridge, a screw threaded socket mounted on the cover plate, a tension plate having one end bearing on the cover plate and the other end bearing on the reciprocating blade, a thumb screw passing loosely through the tension plate and engaging in the socket of the cover plate, and a coil spring confined 10 on the screw between the head of the latter and the tension plate for placing the latter under tension.

4. In a hair clipping device, a casing, a cutter blade fixed at the front end of the 15 casing, a reciprocating cutter blade mounted to slide over the fixed cutter blade, a bearing support at the front end of the casing having a pivot socket, a flat lever having a de-

pending pivot stud engaging in the socket and mounted to swing on said support, the 20 front end of the lever engaging the reciprocating blade, the rear end of the lever having a longitudinal slot, a gear mounted in the casing and having an eccentric driving element engaging in the slot of the lever, 25 means for rotating said gear to swing said lever, a cover plate fastened on the casing and engaging the upper side of the lever for confining the same on its pivot support, and a spring pressed tension plate contacting 30 with the reciprocating cutter blade and having spring tensioned engagement with the cover plate.

In testimony whereof I affix my signature.

COLLIER MONROE.
